COMBINED FLAG MAST AND LIGHT

Herbert Alton Cook, Jr., Auburn, N.Y.

Application November 3, 1958, Serial No. 53,263

Term of patent 14 years

(Cl. D71—1)

Figure 1 is a side elevation of a combined flag mast and light embodying my new design;

Figure 2 is an enlarged transverse section through the base portion of the mast taken substantially along line 2—2 of Figure 1;

Figure 3 is a fragmentary elevation of the base portion of the mast rotated through 90° from the position shown in Figure 1.

I claim:

The ornamental design for a combined flag mast and light, substantially as shown.
